(57) CLAIM

We claim the ornamental design for a wardrobe box assembly, as shown and described.

DESCRIPTION

FIG. 1 is a perspective view of a wardrobe box assembly.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines, the areas within them, and the unshaded areas bounded by broken lines and solid lines depict portions of the wardrobe box assembly that form no part of the claimed design.
